LOADING DEVICE FOR DRAFTING ARRANGEMENTS

Eduard Eggenschwyler, Winterthur, Switzerland, assignor to Joh. Jacob Rieter & Co. Ltd., Winterthur, Switzerland, a corporation of Switzerland

Filed Jan. 30, 1957, Ser. No. 637,182

Claims priority, application Switzerland Feb. 15, 1956

5 Claims. (Cl. 19—135)

The present invention relates to a loading system for drafting arrangements in spinning machines and more particularly to a loading system for the top rolls of drafting arrangements whereby the load is produced by means of a pressure fluid.

Top rolls of drafting arrangements which rolls are indirectly loaded by a pressure fluid have been proposed. In the conventional arrangements the load is transmitted by levers to the top rolls. The conventional systems are all unsatisfactory because the adjustability of the range within which the load conditions change is very limited.

Directly pneumatically loaded top rolls have been proposed which are located within the carrier of the top rolls, the carrier being constructed as a guide arm. Because of the small available space, this arrangement is suitable only for medium sized loads and cannot be used for great loading forces.

The shortcomings and limitations of the aforementioned conventional systems are avoided with the arrangement according to the invention in which the transmission of the load from an internally pressurized oblong elastic hollow body whose longitudinal axis is normal to the rotation axes of the top rolls is effected through a plurality of shoes resting on the hollow body and being tiltable relatively to each other in a direction which is parallel to the longitudinal axis of the body. Groups of the shoes are individually engaged by pressure transmitting elements which are individually operatively connected with the top rolls in such a manner that the sum of the forces transmitted from the pressure shoes of a group to the respective transmitting element is the same at any position of the top rolls and of the transmitting element relatively to the longitudinal extension of the elastic body.

The novel features which are considered characteristic of the invention are set forth with particularity in the appended claims. The invention itself, however, and additional objects and advantages thereof will best be understood from the following description of embodiments thereof when read in connection with the accompanying drawing in which:

Fig. 1 is a diagrammatic elevation of a loading system according to the invention for a drafting arrangement;

Fig. 2 is a cross sectional view of the lower part of the loading system shown in Fig. 1;

Fig. 3 is a vertical longitudinal sectional view of the lower part of the system shown in Fig. 1;

Fig. 4 is a longitudinal vertical view of the lower part of a modified loading arrangement.

Like parts are designated by like numerals in several figures of the drawing.

Referring more particularly to the drawing, numerals 1 to 6 designate fluted rollers which form together with top rolls 7 to 10 a conventional drafting arrangement. In order to adjust the spacing of the nips formed by the fluted rollers and the top rollers according to the staple of the materials to be worked, it is necessary that the position of the top rolls can be changed longitudinally of the

2

drawing frame. Each top roll is loaded at both ends by means of a tension rod 11 forming part of a pressure transmitting element. The latter includes a hook 12 which is adjustably connected with the lower end of the rod 11 by means of a screw connection, the hook including a ridge portion 13 (Fig. 2) which is connected with the screw connection by an arcuate portion 14 whose upper end is provided with an aperture for receiving the threaded lower end 15 of the rod 11. The load forces are produced in an internally pressurized hose 17 which is received in an inverted U-shaped channel 16. A plurality of pressure shoes 18 transmit the pressure from the hose 17 to the ridge portion 13 of the hook 12. The ends of the channel 16 are rigidly connected with a portion of the frame 20 of the spinning machine which is provided for this purpose with suitable recesses 19. A portion of the frame 20 is shown in Fig. 2.

The channel 16 has two leg portions, 21 and 22, which are provided with internally projecting flanges 24 and 23, respectively, leaving a longitudinal slot 25 below the longitudinal axis of the tube 17. The aforesaid pressure shoes 18 are placed between the hose 17 and the flanges 23 and 24, each shoe having two downwardly projecting protuberances 26 and 27 forming a V-shaped recess 28. The bottoms of the recesses are substantially parallel to the longitudinal axis of the hose 17 and are adapted to receive the ridge 13 of the hook 12. The pressure shoes 18 have shoulders 29 which rest on the flanges 23 and 24, preventing falling of the pressure shoes out of the channel 16 when the shoes are not supported by or are not pressed against the ridge portion 13 of the hook 12.

The pressure shoes 18 are provided with head portions 30 having two oppositely positioned lateral substantially cylindrical surfaces 31 and 32 which abut against corresponding surfaces on the neighboring pressure shoes. This prevents jamming, if the shoes move relatively to each other towards and from the axis of the hose 17.

As is evident from Fig. 3, the sum of the forces transmitted from the pressure shoes 18 to the hook 12 remains the same and is independent of a displacement of the hook 12 along the longitudinal axes of the hose 17 and of the channel 16. If the force transmitted from the hose 17 to a shoe 18 has the value P , a force $P+P$ acts on the hook 12 in the position shown in Fig. 3 which force is exerted by the shoes which are completely in engagement with the ridge portion 13; in addition there is a force $2 \times P/2$ derived from the shoes of which only a part rests on the ridge portion 13.

A reaction $P/2$ is transmitted from the shoulders of the shoes of which only a portion engages the ridge portion 13 to the flanges 23 and 24. The total of the loading forces amounts to $3P$. There is another possible position of the hook 12, if the latter is provided with a ridge portion substantially as long as the total length of the space taken by three abutting pressure shoes. In this position three pressure shoes rest entirely on the ridge portion so that the force exerted on the hook 12 is again $3P$. In this case there are no additional $P/2$ reactions because the pressure shoes which are on the left and on the right of the three shoes engaged by the ridge portion 13 do not take any hold on the ridge portion. It is, therefore, clear that the force transmitted from the hose 17 through the pressure shoes 18 to the hook 12 is always the same and independent of the position of the hook 12 longitudinally of the hose 17. Of course, in actual practice this load may change up to 20% and such minor changes are included, if the term "constant" load is used in this specification and in the appended claims. This variation of the load is caused by friction effects which cannot be completely eliminated. The more flexible the hose 17 the more the load is likely to be the same in

different positions of the hook 12 relatively to the hose 17.

The length of the ridge portion is preferably so that never more than three pressure shoes transmit their entire force to the hook 12. A particularly suitable length of the ridge portion has been found to amount to the space taken up by two and one half adjacent pressure shoes. If the structure of the drafting arrangement permits this, the number of pressure shoes acting on the ridge portion of the hook 12 may be increased to three and one half or to four and one half, i.e., to n minus one half, n designating the number of the transmitted pressure shoe loads.

When using a design of the pressure shoes, as shown in Fig. 4, this limitation need not be made to the same extent. The heads 33 of the pressure shoes 32, 32^I, 32^{II}, 32^{III}, 32^{IV}, 32^V are not provided with lateral cylindrical surfaces, but are provided with articulations which prevent a mutual vertical sliding of adjacent heads. As seen in Fig. 4, the heads 33 are provided on one side with an edge portion 34 and on the other side with a recess 35 which is adapted to receive the edge portion 34 of the head of the adjacent pressure shoe. In the modification shown in Fig. 4, the forces transmitted from the pressure shoes to the hook 12 remain the same and are independent from the position of the hook 12 along the longitudinal extension of the hose 17. The ridge portion 13 of the hook may decline slightly from the longitudinal axis of the hose 17 towards the ends of the ridge portion because the position of the pressure shoes 32 is not defined by the abutment of the shoulders of the pressure shoes against the flanges of the channel and by the engagement of the V-shaped recess of the pressure shoe with the ridge portion, as is the case in the modification shown in Fig. 3. The pressure shoe 32^I, which is in inclined position, is held on its left side by the edge 34 received in the recess 35 of the adjacent pressure shoe 32 which absorbs the reaction $P/2$. The right side of the pressure shoe 32^I sits on the ridge portion 13. The modification shown in Fig. 4 has the advantage that there are no edges which cut into the hose 17 and the hose rests more smoothly on the heads of the pressure shoes. The result is increased accuracy of load distribution. Instead of providing edges 34 and complementary recesses 35, the articulations may be made by providing spherical protuberances and corresponding cavities.

The loading arrangement according to the invention operates accurately only if the tension rods and respective hooks are always at a right angle to the longitudinal axes of the channel 16 and of the tube 17.

This requirement is complied with in horizontal drafting arrangements, as in drafting frames, and the like, and there are no special provisions needed for applying the invention. The described and illustrated loading arrangement is particularly suitable for drafting arrangements of this kind.

I claim:

1. A loading device for the top rollers of a drafting arrangement including an internally pressurized elastic hollow body, a plurality of pressure shoes resting against the outside of said body, and a pressure transmitting element interposed between a plurality of said shoes and one of the top rollers and having a first portion engaging a plurality of said shoes, said pressure transmitting ele-

ment having a second portion engaging a top roller, said elastic hollow body being in the form of a hose and said pressure shoes being arranged in a row substantially parallel to the longitudinal axis of the hose, said pressure

5 shoes having head portions of a greater peripheral extension than the rest of said shoes, said head portions engaging said hollow body and laterally engaging the head portions of neighboring shoes, said head portions being so shaped as to afford relative tilting of adjacent pressure 10 shoes and simultaneous retention of the positions of the pressure shoes relatively to the longitudinal axis of said hose.

2. A loading device according to claim 1 in which the length of said first portion amounts to n minus one 15 half of the dimensions of said pressure shoes measured between the points of engagement of said pressure shoes, n designating the number of loads produced by the individual pressure shoes which number is desired to be transmitted by said pressure transmitting device.

3. A loading device according to claim 1 in which said head portions are provided with articulations interconnecting the head portions of neighboring shoes.

4. A loading device according to claim 3 in which said first portion of said pressure transmitting device declines from the center line of said hose at either end of 25 said first portion.

5. A loading device for the top rollers of a drafting arrangement including an oblong channel element whose longitudinal axis extends substantially normal to the rotation axis of the top rollers, an internally pressurized oblong elastic body received in said channel element in parallel relation thereto, a plurality of pressure shoes placed in said channel element adjacent to one another to form a continuous line parallel to the longitudinal 30 axis of said body, said channel element having a longitudinal opening, said shoes resting against the outside of said body and facing the opening of the channel element, said shoes being individually tiltable on axes which are normal to the longitudinal axis of said body, and a pressure transmitting element interposed between a plurality of said shoes and one of the top rollers and having a first portion engaging a plurality of said shoes, said pressure transmitting element having a second portion 35 engaging a top roller, said pressure shoes including portions located inside and cooperating with the inside of said channel element for retaining said shoes inside said channel element, all said pressure shoes having the same size and configuration and being tiltable relatively to each other for transmitting a pressure equal to the sum of the 40 pressures exerted by the individual pressure shoes engaged by said first portion of said pressure transmitting element to the latter independently of which of the pressure shoes are engaged by said first portion.

55 45 50 55 60 65 70 75 80 85 90 95 100

5. A loading device for the top rollers of a drafting arrangement including an oblong channel element whose longitudinal axis extends substantially normal to the rotation axis of the top rollers, an internally pressurized oblong elastic body received in said channel element in parallel relation thereto, a plurality of pressure shoes placed in said channel element adjacent to one another to form a continuous line parallel to the longitudinal axis of said body, said channel element having a longitudinal opening, said shoes resting against the outside of said body and facing the opening of the channel element, said shoes being individually tiltable on axes which are normal to the longitudinal axis of said body, and a pressure transmitting element interposed between a plurality of said shoes and one of the top rollers and having a first portion engaging a plurality of said shoes, said pressure transmitting element having a second portion engaging a top roller, said pressure shoes including portions located inside and cooperating with the inside of said channel element for retaining said shoes inside said channel element, all said pressure shoes having the same size and configuration and being tiltable relatively to each other for transmitting a pressure equal to the sum of the pressures exerted by the individual pressure shoes engaged by said first portion of said pressure transmitting element to the latter independently of which of the pressure shoes are engaged by said first portion.
